UNITED STATES PATENT OFFICE.

ERNEST A. HUMMEL, OF ST. PAUL, MINNESOTA, ASSIGNOR TO ALBERT L. HAMAN, OF ST. PAUL, MINNESOTA.

GRAVITY-ESCAPEMENT FOR CLOCKS.

1,097,637.

Specification of Letters Patent. Patented May 26, 1914.

Application filed August 25, 1911. Serial No. 646,025.

To all whom it may concern:

Be it known that I, ERNEST A. HUMMEL, a citizen of the United States, residing at St. Paul, in the county of Ramsey and State 5 of Minnesota, have invented certain new and useful Improvements in Gravity-Escapements for Clocks, of which the following is a specification.

My invention relates to improvements in 10 gravity escapements for clocks, its object being to provide a gravity escapement which shall be simple and efficient, and which can be used in short pendulum clocks to make the seconds hand beat once instead of twice 15 with every double swing of the pendulum.

It is desirable for time comparison and other reasons that the seconds hand should beat seconds, but in many clocks a seconds pendulum, that is a pendulum which makes 20 one oscillation or single swing in a second, would be inconveniently long, so that resort has been had to a short pendulum which makes one oscillation every half second. This, with the escapements now in use, 25 causes the seconds hand to beat half seconds. The escapement which is the subject of this invention, however, when used with such a pendulum, will cause the seconds hand to beat seconds instead of half seconds. One 30 embodiment of the invention is shown in the accompanying drawings, in which—

Figure 1 is a front view of the escapement mechanism, partly broken away, showing the escape wheel held at rest and the gravity 35 pallet swung almost out of the orbit of the lifting pins; Fig. 2 is a similar view, but showing the escape wheel released from the stop pallets and the gravity arm receiving its return impulse from the escape wheel; Fig. 3 is a side view of the escapement 40 mechanism; Fig. 4 is a detail showing the position of the gravity pallet when lifted by the final impact of the pendulum; and Fig. 5 is a perspective view of the stop 45 pallets.

In the drawings A represents the frame of the clock, B the pendulum, and C the escape wheel, which is here shown as a star wheel with six long teeth or leaves. The escape 50 wheel is fast upon the arbor 2, and is

driven from the seconds hand arbor 3 by means of the meshing gears 4 upon the seconds hand arbor and 5 upon the escape wheel arbor 2. Also fast upon the arbor 2 and rotatable with the escape wheel are six 55 lifting pins 6, here shown integral with the escape wheel and in the form of peripheral teeth upon the hub thereof.

Fast upon the arbor 7 above the escape wheel and suspended therefrom is a one 60 legged gravity arm D, having at its lower end a pin 8 in position to engage the pendulum. The gravity arm is outwardly bowed, and at its middle point has an inwardly projecting lug 9 carrying a pallet 10 in position 65 to be engaged successively by the lifting pins 6 of the escape wheel. I have herein called this pallet the "gravity pallet" to distinguish it from the stop pallets hereinafter mentioned.

Fast upon the arbor 7, and preferably integral with the gravity arm D as shown in the drawings is a crank arm 11 having an in-turned finger 12 which forms an outer stop pallet for the teeth or leaves of the escape 75 wheel. The arm 11 oscillates up and down as the gravity arm swings back and forth, thereby alternately stopping and releasing the successive teeth of the escape wheel. Pivoted supported upon the frame at 13 80 on the other side of the arbor 7 is a long arm 14, terminating in an in-turned finger 15 which lies just within and in juxtaposition to the finger 12 and forms an inner stop pallet for the teeth of the escape wheel. The 85 pallet arm 14 rests normally upon a stud 16 upon the frame, and is periodically lifted by the gravity arm by means of a pin 17 upon a crank arm 18 which is fast upon the arbor 7 and extends in an opposite direction 90 from the crank arm 11.

In operation, when the pendulum has nearly reached the limit of its return or outward swing to the right, the parts will stand in the position shown in full lines in Fig. 1, 95 with one of the teeth of the escape wheel held by the outer stop pallet 12, and the gravity arm held out by a lifting pin with its pallet 10 almost out of the orbit of travel of the pin. The pendulum in its return swing to 100

the right has just reached the lower end of the gravity arm and its impact upon the pin 8 will move the gravity arm just enough farther to lift the outer stop pallet and release 5 the intercepted tooth of the escape wheel, and at the same time to lift the pallet 10 out of the orbit of the lifting pin, as shown in Fig. 4. This movement of the pendulum and gravity arm is very slight, as will be 10 seen from the dotted lines in Fig. 1 indicating the final position of the pendulum. The escape wheel is thus free to move, but its released tooth will be immediately intercepted again by the inner stop pallet 15. In the 15 meantime the gravity arm, whose pallet 10 is now clear of the lifting pin, will swing inwardly, driving the pendulum before it, and at the same time raising the crank arm 18 until the pin 17, acting upon the arm 14, 20 lifts the inner stop pallet 15 sufficiently to release the intercepted tooth of the escape wheel. The release will occur just before the gravity pallet 10 reaches and lodges against the next lifting pin, as shown in 25 dotted lines in Fig. 1. In this forward movement of the gravity arm the outer stop pallet 12 will be turned down again into the path of the escape wheel. When thus released, the escape wheel will turn in the direction of 30 the arrow, as shown in Fig. 2, until the next succeeding escape tooth is stopped by the outer pallet 12, and its lifting pin, acting upon the gravity pallet 10, will lift the gravity arm and swing it back to the locked 35 position shown in full lines in Fig. 1, while the pendulum will continue its oscillation to the left independently of the gravity arm. The crank arm 18, which works with the gravity arm, will at the same time be turned 40 down away from the arm 14 so as to permit the inner stop pallet carried thereby to drop down again into the orbit of the escape teeth. The pendulum will in the meantime have completed its oscillation to the left and overtaken 45 the gravity arm in its return swing to the right. The impact of the pendulum upon the gravity arm, which is now held out by the lifting pin, will move the gravity arm just enough farther to release the escape 50 tooth from the stop pallet 12 and the gravity pallet 10 from the lifting pin, as described above, and another forward swing of the gravity arm and pendulum will take place. By holding the gravity arm out, as shown in 55 Fig. 1, until the pendulum overtakes it, the pendulum will be enabled to complete its full return swing without interference from the gravity arm, and the impulse of the gravity arm will always be first communicated to the 60 pendulum at the beginning of its forward swing, the impact of the pendulum being utilized to release the gravity arm from the lifting pin. Thus the escape wheel will be permitted to make only one effective turning

movement at each double swing of the pendulum, for the release movement from the stop 12 to the stop 15 is so small as to be practically negligible in its effect upon the seconds hand. The seconds hand will thus be made to beat but once with each double swing of 70 the pendulum, so that if the pendulum is a half second pendulum the seconds hand will beat seconds instead of half seconds.

The term "lifting" is used in the claims to indicate broadly the moving of the stop 75 pallets out of the path of the escape wheel, whether such movement be up, down, to one side or otherwise.

I claim as my invention:

1. In an escapement for clocks, the combination with the pendulum and escape wheel, of a one legged gravity arm, a pair of juxtaposed stop pallets for the escape wheel, whereby successively to intercept the same tooth of the escape wheel, pendulum actuated means for lifting one of said pallets and means independent of the pendulum for lifting the other of said pallets.

2. In an escapement for clocks, the combination with the pendulum and escape 90 wheel, of a one legged gravity arm and a pair of juxtaposed stop pallets operated thereby, whereby successively to intercept the same tooth of the escape wheel, one of 95 said pallets being lifted as the gravity arm swings in one direction and the other pallet being lifted as the gravity arm swings in the opposite direction.

3. In an escapement for clocks, the combination with the pendulum and escape wheel, 100 of a one legged gravity arm impelled by the escape wheel in one direction only and moving in the other direction by gravity only, and a pair of stop pallets operated thereby, one of 105 said pallets being lifted as the gravity arm swings in one direction and the other pallet being lifted as the gravity arm swings in the opposite direction.

4. In an escapement for clocks, the combination with the pendulum and escape wheel, 110 of a pair of stop pallets arranged in the path of the wheel whereby successively to intercept the same tooth of the escape wheel, pendulum actuated means for lifting one of said pallets and gravity actuated means for lifting 115 the other of said pallets.

5. In an escapement for clocks, the combination with the pendulum, and the escape wheel, of a gravity arm, a pair of juxtaposed stop pallets one of which is carried by the 120 gravity arm and actuated thereby under the pendulum-impelled swing of said arm, the other being independently mounted, and means for actuating the independently-mounted pallet by the gravity-actuated fall 125 of the gravity arm.

6. In an escapement for clocks, the combination with the pendulum, and escape wheel,

of a gravity arm, a pair of juxtaposed stop pallets one of which is carried by the gravity arm and actuated thereby under the pendulum-impelled swing of the gravity arm, the other pallet being pivotally-mounted upon the clock frame, and a crank arm for actuating the pivotally-mounted stop pallet, said crank arm being operatively related to the

gravity arm for actuation thereby under the gravity-induced movement of said arm. ¹⁰

In testimony whereof I affix my signature in presence of two witnesses.

ERNEST A. HUMMEL.
